Charles Westerman,

INVENTOR

Victor J. Evans

ATTORNEY

UNITED STATES PATENT OFFICE.

CHARLES WESTERMAN, OF BROOKLYN, NEW YORK.

FOOTSTOOL.

Application filed November 22, 1927. Serial No. 235,083.

This invention relates to improvements in foot stools.

The primary object of the invention resides in a foot stool which is light in weight for facilitating the easy handling of the same during shipment and when in use, and which is accomplished by providing a relatively hollow reinforced body having an outer covering of decorative material thereon which 10 in appearance resembles the foot stools now on the market.

Another object of the invention is to provide a foot stool made of a fibre box-like structure of any desirable shape having 15 spaced reinforcing fibre walls for bracing all of the walls of the body to prevent any possible collapse thereof when subjected to any ordinary strains.

A further object is to simplify the construction and manufacture of foot stools, and reduce the cost thereof.

With these and other objects in view, the invention resides in certain novel construction and combination and arrangement of 25 parts, the essential features of which are hereinafter fully described, are particularly pointed out in the appended claims, and are illustrated in the accompanying drawing, in which:—

30 Figure 1 is a perspective view of my improved foot stool with a portion broken away in section.

Figure 2 is a vertical sectional view therethrough.

35 Figure 3 is a horizontal sectional view on the line 3—3 of Figure 2.

Figure 4 is a perspective view of the body of the stool with the reinforcing element removed therefrom.

40 Referring to the drawings by reference characters, the numeral 10 designates my improved foot stool in its entirety which includes a box-like fibre body 11 of any desired shape and which is constructed of reinforced 45 cardboard such as used in cardboard cartons and the like. In reality, the body is no more than a cardboard carton and in the present instance, the same is shown as rectangular in configuration and comprises side walls 12,

50 bottom wall 13, and top wall 14. The side walls are continuous but the top and bottom walls are formed by a plurality of foldable flaps 15 hinged to the side walls and foldable to a position to overlap each other and provide an entirely closed top and bottom walls.

Contained within the body 11 is a fibre re-

inforcing element 16 which is fitted into the body through either the top or bottom when the flaps are in an open position, and which comprises a plurality of spaced longitudinal 60 walls 17 and a plurality of spaced transverse walls 18. The walls 17 and 18 are suitably notched to provide interlocking engagement with each other at their intersections, the spaces between the walls defining hollow cells 65 which lightens the weight of the body. By reason of the crossing of the reinforcing walls, and the fact that the element 16 snugly fits within the box-like body, the walls of the body will be rigidly braced on all sides. 70

A layer of padding material 19 is placed on the top wall 14 of the body and a covering of velour 19' or other decorative material is applied over the top and sides of the body and folded under the bottom where the free 75 edges of the material are brought taut and held by stitching or the like. A strip of oil-cloth or the like 20 overlaps the free edges of the covering 19' and is suitably stitched thereto to give the bottom a finished appearance and protect the bottom from wear when sliding the stool over the floor. A cord 21 passes centrally through the body and has buttons 22 at opposite ends thereof abutting the top and bottom of the stool to compress 80 the padding to hold the top of the covering smooth and impart thereto, the appearance of a cushion. Tabs 23 extend from the sides of the foot stool by which it may be picked up for transporting from place to place in a 85 room.

From the foregoing description, it will be manifest that I have constructed a foot stool which is exceptionally light in weight, strong and rigid in construction, and which has all 95 of the outward appearances of the solid foot stools now on the market.

While I have described what I deem to be the most desirable embodiment of my invention, it is obvious that many of the details 100 may be varied without in any way departing from the spirit of my invention, and I therefore do not limit myself to the exact details of construction herein set forth nor to anything less than the whole of my invention limited 105 only by the appended claims.

What is claimed as new is:—

1. A foot stool comprising a hollow box-like body, spaced reinforcing walls within said body, a padding of material upon the top of said body, an outer covering of material 110 passing over said padding and the walls of

said body and fixed thereon, and a binding cord passing through said body, padding and covering and having buttons on the free ends thereof.

5 2. A foot stool comprising a hollow box-like body, spaced reinforcing walls within said body, a padding of material upon the

top of said body, and an outer covering of material passing over said padding and around the exterior walls of said body and fixed thereon.

In testimony whereof I have affixed my signature.

CHARLES WESTERMAN.
